COMBINATION SOAP DISPENSING DEVICE
AND HAND DRIER

Louis L. Siegel, Lakewood, Ohio

Application May 12, 1947, Serial No. 747,573

4 Claims. (Cl. 146—63)

1

The present invention relates to a soap dispensing device and hand drier, and more particularly to a device for furnishing granulated soap for toilet use and for providing a hot air blast for hand drying.

It is common practice, particularly in public washrooms, to provide devices for dispensing soap in granulated form for toilet use. These devices generally consist of a container having a metering valve in the lower part thereto for discharging a relatively small quantity of granulated soap when the valve is operated. These dispensers, however, are quite unsatisfactory in that granulated soap will, due to the collection of moisture therein by condensation and absorption, become lumpy or form cakes which will not flow from the container, rendering the dispenser useless until an attendant can break up the lumps. Many attempts have been made to correct this fault by rendering the soap free flowing regardless of moisture. Generally, certain chemicals are intermixed with the soap, but these chemicals are expensive and render the soap undesirable.

Another limitation of the usual soap dispenser is that some users prefer certain brands of soap which may be available in bar form only and those dispensers are useless in such cases.

An object of the present invention is to provide a soap dispensing mechanism which not only assures that the granulated soap will be maintained in free flowing condition without the addition of foreign chemicals to the soap, but which will also act upon bar soap to granulate the same so that the desired kind of soap may be employed whether it is in granulated or bar form.

Another object of the invention is to provide a soap dispensing device which has power driven mechanism for either granulating bar soap or for breaking up previously granulated soap so that a free flow of granulated soap may be delivered from a chute to the user's hands, and in which an air blower is also driven by the power mechanism for furnishing a hot air blast for drying the hands.

Still another object of the invention is to provide a device for dispensing soap through a tube, means being provided for preventing the accumulation or adhesion of soap to the walls of the discharge chute.

Other objects and advantages of the invention will be apparent from the following description of a preferred form of embodiment of the invention, reference being made to the accompanying drawings wherein:

Fig. 1 is a front view of the soap dispensing and hand drying device, certain parts of the device being broken away;

Fig. 2 is a top view of the device taken on line 2—2 of Fig. 1;

2

Fig. 3 is a side view of the device showing the device mounted on a wall;

Fig. 4 is a view in section taken substantially along line 4—4 of Fig. 2, but on a larger scale;

Fig. 5 is a view in section taken on line 5—5 of Fig. 4;

Figs. 6 and 7 are perspective views, respectively, of two soap dispensing valve members; and

Fig. 8 is a wiring diagram for the device.

Referring to the drawings, I have shown a combination soap dispensing and hand drying device 10. The device 10 is preferably enclosed in a suitable housing indicated at 11, which housing may be formed in any suitable manner, and in the drawings it is shown in a more or less diagrammatic form. The housing is formed of a bottom wall 12, front and rear walls 13 and 14, and end walls 15 and 16. The top of the housing 11 is adapted to be closed by a cover 17, which may be removably secured to the housing by any suitable means, not shown. The end wall 15 is provided with a circular opening 18 for admitting air to a blower within the housing, and preferably the opening 18 is covered by a grill indicated at 19.

The housing 11 is attached to a wall by suitable brackets, not shown, and for the sake of convenience it is desirable to mount the device 10 immediately above or adjacent to a wash bowl.

A soap container 22 is mounted inside the housing on a bracket 23 which is secured to the bottom wall 12 of the housing. The container 22 is preferably formed of a rectangular box-like structure open at the top and having sloping walls 24 at the bottom. Preferably, a cover 25 is provided for the top of the container and it is desirable to provide a locking device, not shown, for securing the cover in place. The lower edges of the walls 24 are spaced from one another and a sleeve 26 extends lengthwise of the space between the two lower edges of the sloping walls and it is attached to these lower edges, as by welding. The sleeve 26 is provided with two rectangular openings 27 and 27' formed in the top and bottom thereof through which soap granules may pass. A rod-like valve member 30 is rotatably positioned in the sleeve 26 and it is secured therein by a nut 31 threaded on one end thereof and a gear wheel 32 secured on a stem portion 33 of the rod. The gear wheel may be keyed to the rod 30.

The rod 30 is provided with grooves 35 and 35' on opposite sides thereof, which grooves are in registration with the openings 27 in the sleeve 26 when the rod 30 is rotated to the proper degree. As may be seen in Fig. 5, when groove 35 is exposed to the soap in the container through the upper opening 27, the groove 35' will be in a position to discharge soap through the lower opening 27' in the sleeve.

A discharge chute 36 is attached to the bottom walls 24 of the container and it surrounds the lower opening 27' in the sleeve 26 for directing the soap downwardly to a forwardly and downwardly extending tube 37 which is attached to the chute 36 and which extends through an opening in the front wall 13 of the housing for discharging soap on to the hands of the user.

The stem 33 of the rod 30 extends outwardly through the front wall 13 of the housing and a handle 38 is attached to the stem. Also attached to the stem 33 is a hammer member 40 which is provided with a head part 41 that is adapted to strike the side of the tube 37 when the handle 38 is rotated clockwise as viewed in Fig. 1. The purpose of this hammer member is to dislodge any soap granules which may adhere to the walls of the tube 37. A tension spring 42 is attached at one end to the hammer member 40 and the other end to the bottom of the housing 11. The spring 42 and hammer 40 normally maintain the valve rod 30 in the angular position indicated in Fig. 5 so that the groove 35 will be in a position to be filled with soap granules after the handle 38 is released by the operator. When the handle 38 is depressed to rotate the valve rod 30 counter-clockwise as viewed in Fig. 1, the groove 35 will be rotated to discharge soap therein through the lower opening 27' in the sleeve and the opposite groove 35' will be in a position to receive soap through the upper opening 27 in the sleeve. Then when the handle 38 is released the groove 35' will be moved to the position shown in Fig. 5 to discharge its soap through the lower opening 27 as the handle 38 returns to its normal inoperative position. Preferably, the counter-clockwise rotation of handle 38 is limited by a screw 45 which projects laterally from the nut 31 and which is adapted to engage a stop 46 attached to the support bracket 23.

In order to maintain the soap in the container 22 in a free flowing granular state, I have provided a helical member 48 in the container immediately above and parallel to the sleeve 26, and the helical member preferably consists of a wire spring mounted on a rod 49 journaled in the front and rear walls of the container 22. The forward end of the rod 49 projects through the front wall of the soap container and has a gear pinion 50 attached thereto which meshes with the gear wheel 32. As the valve rod 30 is rotated by handle 38, gear 32 drives the pinion 50 which rotates rod 49 and causes the helical member 48 to agitate and break up any lumpy soap particles immediately above the opening 27 in the sleeve 26. It will be apparent that the member 48 will be rotated in opposite directions when the handle 38 is lowered and raised during a soap dispensing operation. Thus, the soap in the container 22 at the opening 27 will be maintained in a free flowing condition by the action of the member 48.

It is often desirable to obtain the soap granules from a bar of soap, and for this purpose a rotary soap cutter 52 is mounted in the soap container 22 and is driven by an electrical motor. The cutter 52 is shown consisting of a flanged wheel structure having a number of blades 53 formed from the flanged portion of the wheel. The blades 53 are formed by cutting slots in the flange of the wheel and twisting the cut portions to extend radially and thereby provide cutting edges extending parallel to the axis of the wheel. The cutter 52 is mounted on an axle 54 which extends through the rear wall of the container 22 and the axle 54 is driven by an electric motor 55 through

a suitable gear reduction box 56. The soap bar is placed in the container through the open top and rides on the peripheral blades of the cutter. Preferably, a weight is placed on the soap to press it on the blades. When the cutter rotates the soap bar is shaved and these particles drop to the lower part of the container and are broken into granules by the member 48.

Powdered or granulated soap may be used instead of bar soap. In this instance the cutter wheel 52 will maintain the soap in its powdered condition and it is evident that either type of soap may be used, as desired.

The motor 55 is supported on two cross-members 57 of the housing 11, one end of the armature shaft of the motor being connected to the gear reduction box 56 and the opposite end having a centrifugal blower 58 mounted thereon.

The blower 58 is shrouded by a suitable housing 59 having a central opening 60 at one side thereof for admitting air to the blower and having a nozzle structure 62 leading to the front wall 13 of the housing 11 and in registration with an opening in the front wall. The housing 59 is supported by a bracket 61.

A tubular elbow or deflector 63 is attached to the front wall in registration with the outlet of the nozzle 62 for directing air from the blower downwardly on to the hands of the user. Preferably, an electrical heater unit, shown diagrammatically at 65, is mounted in the nozzle structure 62 for heating the air as it passes to the deflector 63. The electrical unit includes a resistance wire 66 mounted on a suitable insulator, the details of which are not shown, as such is well known in the art, and one end of the resistance wire is connected to a wire 68 and the other end to a wire 69. The resistance wire is connected in parallel circuit with the motor 55 and both motor and resistance are controlled by a treadle actuated switch 72.

In order to maintain the soap granules in the container 22 dry to prevent caking or lumping, I have provided an air conduit 75, one end of which extends into the nozzle structure 62 and the opposite end of which extends into a side wall of the soap container 22 beneath the soap cutter 52. The end of the tube 75 extending into the nozzle structure 62 is cut diagonally so that a scoop effect is provided for directing air into the tube. It will be noted that the air intake of the tube 75 is disposed to receive heated air so that the soap in the container will be dried more effectively.

In operation, the device may be attached to any suitable support, and in the present instance I have shown it attached to a wall. Power for the motor and heater element is supplied through a cord and plug 76 which may be connected in the building outlet socket. The circuit for the motor 55 and the heater element 65 is controlled by switch 72 which is adapted to be actuated by a rod 77 which may be raised by a treadle 78 mounted on a bracket 79 on the floor. When the treadle 78 is depressed switch 72 is closed, completing a circuit from a wire 80 of the power supply line to motor winding 81 and back to the wire 82 of the power circuit, and the heater 65 is connected in parallel with the motor by the wires 68 and 69. The power wires 80 and 82 are part of the plug and cord indicated at 76.

It will be seen that when the device is used for drying the hands the soap cutter will be operated to granulate soap from a bar and heated air would be supplied to the soap container 22 to maintain the soap in free flowing condition. When the

soap dispenser is used the helical member 48 is actuated to further granulate the soap in the container and the hammer 40 maintains the discharge tube 37 free of soap particles. In the event granulated soap is used instead of bar soap, the cutter wheel 52 will agitate the granules to prevent lumping. Thus, I have provided a device which is exceptionally adaptable for washrooms and the like which will dispense soap under all conditions and at a minimum cost. Also, towels may be dispensed with which will provide material savings.

This application is a continuation in part of my application, Serial Number 659,390, filed April 3, 1946, now abandoned.

Although I have described but one form of the invention it is to be understood that other forms might be adopted, all falling within the scope of the claims which follow.

I claim:

1. In a combination soap dispensing device and hand drier, a soap container having valve mechanism for discharging soap from the container; an air blower; a shroud structure associated with the blower for directing a stream of air in one path; a heating device in the shroud structure for warming air blown by the blower; and a conduit interconnecting the soap container and shroud structure for directing warm air from the blower into the soap container.

2. In a soap dispensing device, a soap container having an outlet for soap at the bottom thereof; a valve at said outlet comprising a cylindrical member disposed transversely of the outlet and having an opening in one wall thereof, said cylindrical member having an axially extending part thereon; a handle on said part of the valve member for rotating the valve member about its axis; a soap dispensing chute disposed beneath said cylindrical member and having its inlet in alignment with said opening in the cylindrical member when the latter member is rotated about its axis; a striker arm attached to said valve member and extending laterally therefrom, said striker arm being adapted to strike the chute when the cylindrical valve member is rotated to a position in which the opening in said member is upwardly;

and means resiliently urging said member to the last mentioned position.

3. In a soap dispensing device, a soap container having an outlet for soap at the bottom thereof; a chute leading from said chute downwardly; a valve at the inlet of said chute, said valve including an actuating member, and being adapted to receive soap from the container and to empty soap into the chute when the valve is actuated; an arm attached to a moving part of said valve, said arm being adapted to engage said chute when the valve is in the soap receiving position and to be removed from the chute when the valve is actuated to its soap discharging position; and resilient means for urging said valve to the soap receiving position whereby said arm strikes said chute when the valve actuating member is released from the valve actuating position, said arm and chute forming a stop for positioning said valve.

4. In a combination soap dispensing device and hand drier, a soap container having means associated therewith for discharging soap from the container; an air blower structure; a heating device in said blower structure for warming air activated by the blower; and a passageway interconnecting the soap container and blower structure for directing warm air from the blower into the soap container.
